Primary Examiner — Susan Bennett Hattan*Assistant Examiner* — Lauren D McVey(74) *Attorney, Agent, or Firm* — Bass, Berry & Sims PLC(57) **CLAIM**

The ornamental design for a smart desktop, as shown and described.

DESCRIPTION

FIG. 1 is a perspective view of a smart desktop showing our new design with a power icon, icons with labels, and a strip icon shown;

FIG. 2 is a front view thereof;

FIG. 3 is a left side view thereof;

FIG. 4 is a right side view thereof;

FIG. 5 is a top side view thereof;

FIG. 6 is a bottom side view thereof, the broken lines depicting portions of the smart desktop that form no part of the claimed design;

FIG. 7 is a rear side view thereof, the broken lines immediately adjacent to the solid line perimeter of the smart desktop depicting the bounds of the claim and forming no part of the claimed design, while all other broken lines are directed to environment and form no part of the claimed design;

FIG. 8 is a front view thereof shown with a power icon;

FIG. 9 is a front view thereof shown with no icons;

FIG. 10 is a front view thereof shown with icons without labels;

FIG. 11 is a front view thereof shown with a power icon and a strip; and,

FIG. 12 is a front view thereof shown with a circular icon.

1 Claim, 12 Drawing Sheets(56)
